UNITED STATES PATENT OFFICE

2,593,777

DEVICE FOR MILLING KEYWAY SLOTS

Lewis W. McClelland, Topeka, Kans.

Application July 20, 1949, Serial No. 105,797

5 Claims. (Cl. 90—12)

1

The present invention relates to a mechanism for machining a keyway slot in the butt end of a railway car coupler. The invention more specifically pertains to a portable milling device so constructed that it may be readily handled by a single operator and employed for refinishing used couplers without the necessity of moving the car couplers to a stationary and permanent type of mill machine.

An object of the invention is to provide a keyway slot milling device which may be arranged over the butt end of a railway car coupler and maintained in proper aligned relationship with the keyway slot by the simple expedient of manipulating adjustment screws and the device is so constructed that it need not be dismantled and again assembled to place the cutting tool in operative association with the key slot.

A further object of the invention is to provide a cup-shaped body member which may be arranged over the butt end of a railway car coupler and provided with a tool carrier mounted for guided movement on the cup-shaped body member including means for moving the milling cutter into operative association with the metal to be removed without resorting to the necessity of clamping the body member on the coupler.

Another object of the invention is to provide a milling device with means for indicating the amount of material removed by the cutting tool without stopping the machine to measure the dimensions of the key slot.

A still further object of the invention is to provide a body member for a portable milling device provided with relatively long guide recesses for the legs of a movable U-shaped tool holder to avoid deflection of the milling cutter when force is applied to move the cutting tool into engagement with the metal to be removed.

Other objects and features of the invention will be apparent to those skilled in the art as the present disclosure proceeds and upon consideration of the following detailed description and the accompanying drawings wherein an exemplary embodiment of the invention is disclosed.

In the drawings:

Fig. 1 is a front elevational view of a milling device embodying the invention and illustrating the manner in which the mechanism is arranged on the butt end portion of a railway coupler.

Fig. 2 is a side elevational view of the device.

Fig. 3 is a sectional view taken on the line 3—3 of Fig. 2.

Fig. 4 is a sectional view taken on the line 4—4 of Fig. 1.

Referring to the drawings the rear end portion of a railway car coupler is shown at 10. A

2

number of railway car couplers are provided with a key slot 11 for receiving a horizontal key (not shown) for securing the coupler to the draft gear of a railway car or vehicle. Such a keyway slot 11 becomes worn during use and the present invention is directed to a device for refinishing the slot 11 in the shank of a railway coupler.

A milling device exhibiting the invention includes a cup-shaped body member 12 which is adapted to be arranged over the butt end 14 of the coupler. The body member 12 may be formed of metal plates including a front wall 16 and the plate member forming the front wall may be provided with slots 17 to reduce the weight of the device. One side wall is shown at 18 which is formed of a metal plate provided with an elongated slot 19 as shown in Figs. 2 and 3. A recess 21 of elongated shape is provided in the side wall 18 and this recess and the slot 19 are provided for the purpose of reducing the mass of the device. The rear wall of the body member is shown at 22 and the plate member forming the rear wall is also provided with slots 23 as shown in Fig. 3. These slots 23 correspond in shape and pattern to the slot 17 and are provided for the purpose of keeping the weight of the mechanism to a minimum. The other side wall 24 corresponds in shape and dimensions to the side wall 18. This side wall is provided with an elongated slot 26 corresponding in shape to the slot 19 in the opposite side wall 18. A recess 27 of elongated shape is provided in the side wall 24 to further reduce the weight of the milling mechanism. The top of the body member is covered by a plate 28. This plate may be welded to the front and side walls and the side and end walls of the body member may be welded to each other. The top plate 28 is provided with apertures 29 to further minimize the weight of the device.

The cup-shaped body member 12 is rectangular shaped in cross section and of such dimensions as to be arranged freely over the butt end 14 of the railway car coupler 10. The side walls 18 and 24 each carry an adjustment screw 31 arranged in threaded openings in these side walls. Each adjustment screw 31 is provided with a handle 33 so that the inner ends of these adjustment screws may be moved into engagement with a side face of the coupler shank. The body member 12 may thereby be properly positioned on the butt end of the coupler. In this connection it is to be noted that the screws 31 are not required to carry any of the forces developed during the milling operation but the screws 31 serve to maintain the body member 12 in a

fixed adjusted position relative to the key slot 11.

The front wall 16 of the body member is provided with an elongated recess 36 and the depth of this recess will be apparent from a consideration of Fig. 4. The recess 36 extends throughout the vertical length of the plate which forms the front wall 16 and the top plate 28 is provided with a notch 37 in alignment with the recess 36 to thereby provide an elongated bearing recess for one leg 38 of an inverted U-shaped tool holder 41. The plate member forming the front wall 16 is also provided with a slot 42 at the lower end of the guide recess 36 and this slot 42 is open at its lower end. The purpose of the slot 42 will be more apparent as the present disclosure proceeds.

The rear wall 22 is likewise provided with an elongated recess 51 which extends lengthwise of the body member and is in alignment with a notch 52 provided in the top plate 28. The recess 51 and the notch 52 provide a guide bearing for the leg 54 of the U-shaped tool holder 41. A notch 56 is provided in the lower portion of the rear wall 22 for the purpose of accommodating the milling cutter as hereinafter described. The tool holder or carrier 41 is mounted on the body member 12 with the leg 38 arranged for sliding movement in the recess 36. The leg 54 is arranged for sliding movement within the recess 51 and the intermediate portion of the tool holder 41 extends across the top of the cup-shaped body member.

The invention includes means for preventing the tool holder 41 from unintentional removal from operative association with the body member. In the embodiment illustrated such means include a screw 61 threaded into the leg 54 of the tool holder. This screw carries an unthreaded end portion 62 which extends into a slot 63 in the rear wall 22 of the body member. This slot 63 is elongated as shown in dotted lines in Fig. 1 and of such dimension as to permit a normal stroke of the tool holder 41 in the guide recesses of the body member. The screw 61 is removable to permit assembly of the tool holder 41 on the body member 12 but when the screw end 62 engages the ends of the slot 63 the tool holder is prevented from escaping from association with the body member.

The free ends of the legs of the U-shaped tool holder are provided with bearings for supporting a milling cutter 71 for free rotation. An abrasion resistant bushing 76 is provided in the lower end of the leg 54 to provide a bearing for one end of the milling cutter 71. A bushing 77 is carried by the free end of the leg 38 providing the second bearing for the cutting tool. The cutter may be provided with a tapered shank 78 so that power may be applied thereto for driving the cutter during the milling operation. It will be observed that the cutter 71 extends through the slots 42 and 56 in the front and back walls of the body member and these slots are of such length as to permit the cutter to remove metal from the end of the keyway slot 11 during the milling operation.

The milling device includes an arrangement for moving the tool holder 41 upwardly relative to the body member 12 and the coupler 10. It is for this purpose that a threaded shaft 81 is arranged to engage threads in an opening in the intermediate portion of the tool holder. This shaft may be rotated by means of a hand wheel 82 having a handle 83 mounted thereon. The

body member 12 may be provided with a hardened metal insert or plug 86 having an enlarged head and shrunk or otherwise secured within an opening in the top plate 28. The insert 86 is provided for being engaged by the lower end of the threaded shaft 81.

The milling device is designed primarily for use in refinishing the keyway slot in a railway car coupler but it will be appreciated that the mechanism has utility in other metal cutting operations. When it is desired to redress or re-finish the keyway slot of a coupler the cup-shaped body member 12 with the tool holder 41 arranged thereon and with the milling cutter 71 removed is arranged over the butt end 14 of a coupler as shown in Figs. 3 and 4. It will be observed that the milling cutter 71 is removable from the bearings 76 and 77 by shifting the cutter to the left in Fig. 4. After the body member 12 is in a position, as shown in Fig. 3, with the top plate 28 in substantially abutting engagement with the end of the coupler the screws 31 are adjusted to align the axis of the bearings 76 and 77 with the center line of the keyway slot 11. The inner ends of the screws 31 engage the sides of the coupler shank and thereby maintain the body member 12 in a fixed adjusted position relative to the coupler.

Thereafter the milling cutter 71 or a cutter of similar type is introduced with the free end 91 through the bearing 77 and through the slot 42 and through the keyway slot 11 in the shank of the coupler. The free end 91 is then introduced into the bearing 76. The hand wheel 82 is then turned to rotate the threaded shaft 81 whereby the lower end engages the top of the body member 12 or the plug 86. The tool holder 41 is thereby moved upwardly and the legs 38 and 54 are guided in the elongated recesses in the front and back walls of the body member. Such upward movement of the tool holder moves the cutter 71 into a position to engage the end of the keyway slot 11. The cutter 71 may be rotated to refinish the slot 11 by applying power to the shank 78.

The invention includes means for indicating the quantity of metal removed from the keyway slot. Such means include a scale 96 provided on the outer face of the leg 38 of the tool holder. The front wall 16 carries a bracket 97 having an index 93 overlying the scale 96. Accordingly, by noting the graduation at the beginning of the milling operation the extent of the lengthwise enlargement of the keyway slot can be determined at any instant by observing the graduation opposite the index 93.

After the milling operation has been completed the device may be removed from association with the coupler shank by first retracting the threaded shaft 81 from engagement with the body member or the insert 86. The tool holder 41 is then free to move downwardly whereby the cutter 71 may be withdrawn endwise from the keyway slot 11. Thereafter the screws 31 may be retracted which frees the device for being removed from the end of a coupler. It will be observed that the tool holder 41 cannot be inadvertently detached from the body member since the screw 61 limits the lengthwise movement of the legs of the tool carrier with respect to the body member.

The device adapted for couplers having a shank of as much as six or seven inches in cross section is of weight such as to be capable of being manipulated by a single operator. Accordingly, the milling device may be readily moved to from one

coupler to another. One or both of the legs of the tool holder 41 may be provided with a slot such as shown at 90 extending above the bearing bushing 77 as shown in Fig. 4. This slot is for the purpose of introducing liquid lubricant or cooling agent therethrough and through the slot 42 to facilitate the operation of the cutter 71. It will be observed that the slot 90 is of such narrow dimensions as to prevent the bearing bushing 77 from being dislodged from a position within the opening in the leg 38 of the tool holder.

While the invention has been described with reference to specific structural features and with regard to a detailed arrangement of the parts it will be appreciated that changes may be made in the shape of the elements as well as the general organization. Such modifications and others may be made without departing from the spirit and scope of the invention as set forth in the appended claims.

What I claim and desire to secure by Letters Patent is:

1. A device for milling the keyway slot in the shank of a railway car coupler comprising, a cup-shaped body member having a cross section similar to the cross section of the shank of the coupler adapted to be arranged over the rear end of the coupler shank with a closed end of the cup-shaped body member abutting against the rear end thereof, threaded screws carried by the cup-shaped body member for engaging sides of the coupler shank to adjust the position of the body member on the coupler shank, said body member having an elongated recess in one side thereof arranged lengthwise thereof, said body member having a second elongated recess arranged in the opposite side extending lengthwise thereof, a U-shaped tool holder having legs slideable in said recesses, bearings carried by free ends of said legs, a shaft threaded in an intermediate portion of the U-shaped tool holder adapted to engage the closed end of the cup-shaped body member to move the tool holder relative to the body member, and a detachable milling cutter journaled for rotation in said bearings and adapted to extend through the keyway slot in the coupler shank.

2. In a device for milling a transverse slot in an elongated article, a cup-shaped body member adapted to be arranged over an end of the article and abut against the end of the article means carried by opposite portions of the cup-shaped body member for engaging sides of the article to adjust the position of the body member on the article, said body member having a recess in one side arranged lengthwise thereof, said body member having a second recess arranged in the opposite side extending lengthwise thereof, a U-shaped tool holder having legs slideable within said recesses, bearings carried by the free ends of said legs, a shaft threaded in an intermediate portion of the U-shaped tool holder adapted to engage a closed end of the cup-shaped body member to move the tool holder relative to the body member, and a milling cutter journaled for rotation in said bearings and adapted to extend through said slot in the article.

3. In a device for milling the keyway slot in the shank of a railway car coupler comprising, a cup-shaped body member adapted to be arranged over a butt end of the coupler shank with a closed end of the body member abutting against the butt end of the coupler shank, means carried by opposite portions of the cup-shaped body member for engaging sides of the coupler shank

to adjust the position of the body member thereon, said body member having a recess in one side arranged lengthwise thereof, said body member having a second recess arranged in the opposite side extending lengthwise thereof, a U-shaped tool holder having legs slideable within said recesses, bearings carried by the free ends of said legs, a shaft threaded in an intermediate portion of the U-shaped tool holder adapted to engage the closed end of the cup-shaped body member, a milling cutter journaled for rotation in said bearings and adapted to extend through the keyway slot in the coupler shank, a scale on one leg of the U-shaped tool holder, and an index member carried by the cup-shaped body member overlying said scale.

4. A device for machining a transverse slot within the end of an elongated article comprising, a cup-shaped body member adapted to be arranged over the end of the article with a closed end of the body member engaging the end of the article, threaded screws carried by opposite portions of the cup-shaped body member for engaging sides of the article to adjust the position of the body member on the article, said body member having a recess in one side thereof arranged lengthwise thereof, said body member having a second recess arranged in the opposite side extending lengthwise thereof, a U-shaped tool holder having legs slideable within said recesses, bearings carried by the free ends of said legs, a shaft threaded in an intermediate portion of the U-shaped tool holder adapted to engage the closed end of the cup-shaped body member to move the tool holder relative to the body member, a milling cutter journaled for rotation in said bearings and adapted to extend through said transverse slot, and a detachable abutment member carried by one leg of the tool holder for engaging spaced portions of the cup-shaped body member to limit movement of the tool holder relative to the body member.

5. A device for milling a transverse slot in an elongated article, a cup-shaped body member adapted to be arranged over an end of the article, a pair of threaded screws carried by opposite portions of the cup-shaped body member for engaging sides of the article, said body member having a recess in one side thereof arranged lengthwise thereof, said body member having a second recess in the opposite side extending lengthwise thereof, a U-shaped tool holder having legs slideable within said recesses, bearings carried by free ends of said legs, a shaft threaded in an intermediate portion of the U-shaped tool holder adapted to engage the closed end of the cup-shaped body member, a milling cutter journaled for rotation in said bearings and adapted to extend through said slot, said body member having an elongated opening therein, and an abutment screw carried by one leg of the tool holder for engaging ends of said elongated opening for limiting movement of the tool holder relative to the body member.
